UNITED STATES PATENT OFFICE.

ATHOL B. MACKLIN, OF BROOKLYN, NEW YORK.

HYDROCARBON-VAPOR-BURNING APPARATUS.

SPECIFICATION forming part of Letters Patent No. 707,517, dated August 19, 1902.

Application filed December 11, 1900. Renewed June 13, 1902. Serial No. 111,577. (No model.)

To all whom it may concern:

Be it known that I, ATHOL B. MACKLIN, a subject of the King of Great Britain, and a resident of Brooklyn, in the county of Kings 5 and State of New York, have invented certain new and useful Improvements in Hydrocarbon-Vapor-Burning Apparatus, of which the following is a specification.

My present invention is in the nature of an 10 improvement upon the apparatus covered by Letters Patent of the United States No. 654,408 granted to me July 24, 1900; and the object of my present invention is to improve the construction and operation of the apparatus covered by said patent.

It is very important to the proper operation 15 of vapor-burning apparatus that the vapor-supply nozzle of the vaporizer be kept clear of the natural accumulation of carbon deposit which is carried into the small orifice of the nozzle by the vapor-current passing therethrough and tends to clog the same. For this purpose it is usual to employ an internal needle, such as is shown and described in my 20 above-named patent, No. 654,408. Such a structure is, however, objectionable, not only because it is expensive to make and maintain, but because the great heat of the vaporizer soon anneals the needle and so weakens it that the slightest pressure will cause it 25 to bend and end its usefulness. These internal needles therefore give constant trouble and expense. I propose to overcome this objection to vapor-burning apparatus by providing an external nozzle-cleaning needle 30 which is movably mounted upon the apparatus in such a way that it can be moved into position above the vapor-nozzle and be inserted in the orifice of the nozzle for clearing 35 the same and then be withdrawn from the nozzle and moved away from the nozzle outside of the zone of greatest heat from the vaporizer. Such an arrangement of the needles 40 can best be used with the style of apparatus set forth in my above-named patent, in which the vaporizer and mixing-chamber are arranged with a free space between them, and it is in combination with such an apparatus that I prefer to employ my improved 45 needler.

Another feature of importance in my present invention is the structure of the vapor-

izer proper, which insures a more effective and a more uniform supply of vapor to the mixing-chamber. I construct my improved 55 vaporizer of an outer tubular section, against which the heating-flame is directed, and a bell-shaped section arranged concentrically within the outer section and having communication with the vaporizing chamber or space 60 between them of annular cross-section through suitable ports or openings adjacent to the base of the inner section. The fuel (hydrocarbon oil, such as ordinary kerosene) is supplied through a suitable tube to the 65 base of the inner bell-shaped section and passes therefrom into the annular vaporizing-chamber, the pressure for supplying the oil causing the air in the crown or top of the bell-shaped section to be compressed slightly. 70 The thin film of oil rises in the vaporizing-chamber and is quickly vaporized by coming in contact with the heated surface of the outer wall of the vaporizer and issues at the nozzle in a steady stream of vapor, the cushioning 75 effect of the compressed-air column serving to equalize the pressure of the vapor stream and prevent the possibility of oil under high pressure being projected suddenly into the upper part of the vaporizer and spitting 80 through the nozzle, causing what is known as a "flare-up."

My improvements in vapor-burning apparatus have been designed primarily for a hanging vapor-lamp, which is adapted to be 85 coupled to and supported by the ceiling-tip of the ordinary gas-supply pipe of a dwelling. With this application of my improvements I employ permanent gas-pilots for lighting the burners and a gas Bunsen (lighted by a 90 permanent gas-pilot) for creating the initial heat in the vaporizer. I employ the vertical arrangement of the vaporizer and mixing-chamber with an air-supply space between them, as set forth in my above-named patent, 95 and to avoid the possibility of the products of combustion of the auxiliary vaporizer-heating burner being drawn into the mixing-chamber by the vapor-blast I surround the said auxiliary burner with a cup-shaped shield or 100 deflector.

To facilitate getting at the lamp proper for repair or adjustment, I provide a novel form of globe-support, by which the globe may be

lowered from around the lamp and supported in lowered position or be raised around the lamp and supported in raised position.

In order that my invention may be fully understood, I will first describe the same with reference to the accompanying drawings and afterward point out the novelty with more particularity in the annexed claims.

In said drawings, Figure 1 is an edge elevation, partly broken away, of my improved vapor-burning apparatus. Fig. 2 is an enlarged side elevation, partly in section, of the main parts of the same. Fig. 2^a is a detail view illustrating the arrangement of the wire-15 gauze strip in the mixing-chamber. Fig. 3 is a detail sectional plan view of the improved needling apparatus. Fig. 3^a is a detail projection of part of the needler supporting and guiding tube, showing the guide-slot. Fig. 4 20 is an elevation, partly in section, of a single-burner lamp embodying my improvements. Fig. 5 is an elevation, partly in section, representing a heating-burner embodying my improvements. Fig. 6 is an elevation, partly 25 broken away, showing part of a portable lamp adapted to embody my improvements.

As stated above, the form of my improved vapor-burning apparatus has been designed particularly for lighting purposes in the form 30 of a hanging lamp, which may take the place of the ordinary chandelier for lighting a room, and it may be suspended from the ordinary gas-pipe with which buildings are equipped; but, as hereinafter pointed out, I do not limit 35 myself to this adaptation of my invention.

1 indicates the main supporting tube or pipe of my improved lamp.

2 is an ordinary threaded coupling for securing the pipe 1 to the projecting ceiling-tip 40 of the ordinary gas-pipe.

3 is a double-armed bracket adjustably mounted upon the main pipe 1 by means of the set-screw 4, and 5 and 6 are tubes mounted in the ends of the bracket-arms 3 and depending therefrom. At the lower ends of the tubes 5 and 6 are secured the guide nuts or collars 7 and 8.

10 is a globe-supporting ring upon which is mounted the globe 11, held in place by the 50 thumb-screws 12. The ring 10 is secured to the lower ends of slide-rods 13 by means of nuts 14, which rods 13 extend up into the tubes 5 6 and are provided at their upper ends with locking dogs or fingers 15, which are 55 journaled upon the reduced ends of the guide-rods 13 and are adapted to be placed in line with the guide-rods to allow the guide-rods to move vertically in the tubes 5 and 6 or to be placed at right angles to the guide-rods to 60 engage the upper ends of the tubes and support the guide-rods and connected globe-sustaining ring 10 in elevated position. Just below the upper ends of the guide-rods 13 are mounted adjustable collars 16, which slide 65 freely within the guide-tubes 5 6 and are adapted to engage the nuts 7 8 at the lower ends of said guide-tubes and sustain the

globe-sustaining frame when it is moved to its lowered position. The purpose of this vertically-movable globe-supporting frame is 70 to enable the operator to lower the globe from around the lamp when he desires access to the lamp for adjusting or repairing any of the parts.

20 is an ordinary dished reflector mounted 75 upon the main supporting-pipe 1 between suitable washers 21 22, secured in place by nut 23, threaded upon the upper end of pipe 1. The lower end of the supporting-pipe 1 is bent slightly to one side at 1^a, as shown in 80 Fig. 1, to enable the placing of the lamp proper centrally within the globe-supporting frame. The vapor-lamp proper comprises, essentially, a suitable vaporizer, a mixing-chamber, and burners connected with the 85 mixing-chamber.

25 is a central ring or casting from which extend the upwardly-curved burner-tubes 26, which terminate in the burners 27. The central ring or casting 25 is formed with an integral yoke 30, which is shaped to fit snugly against the lower end of the supporting-pipe 1, to which it is secured by means of the clip or yoke 31, engaging the pipe 1 and secured to the yoke 30 by means of set-screws 32. 95 The ring or casting 25 constitutes the base portion of the mixing-chamber.

35 is the bell-shaped upper and outer portion of the mixing-chamber, which is mounted upon the ring 25.

100

36 is the tubular inner part of the mixing-chamber, formed with open upper end 37 and open lower end 38. This inner tube 36 is adjustably and removably supported within the bell-shaped outer section 35 by means of the threaded connection 39 with the lower wall of the base ring or casting 25. Adjacent to the upper end of the inner tubular section 36 are formed openings 40. The inner tubular section may be provided with a piece of wire-gauze 41, which is slit transversely at its edges 40^a and has the alternate sections bent oppositely, as shown in detail in Fig. 2^a. The wire-gauze 41 is supported upon the upper open end of tube 36 and is for the purpose of more intimately mixing the vapor and air as they pass through the mixing-chamber. The combined vapor and air passes through the open end 37 and openings 40 of tube 36 through the wire-gauze out into the 110 bell-shaped outer section 35 of the mixing-chamber.

115

50 indicates two short tubular sections threaded into openings in the lower face of the casting 25 and supporting at their ends 125 the ring or casting 51 of the auxiliary burner, which surrounds and supports the vaporizer, which I will now describe. The vaporizer comprises an outer tubular section 60, having at its upper end a vapor-nozzle 61 and at 130 its lower end a threaded plug 62, upon which is supported an inner bell-shaped tubular section 63, closed at its upper end 64. The inner tubular bell-shaped section 63 is pro-

vided adjacent to its base with a series of small ports or openings 65, which afford communication between the inner and outer chambers of the vaporizer.

- 5 66 is a fuel-supply pipe leading into the inner tubular section 63 of the vaporizer. The vaporizer is supported from its upper or nozzle end, the nozzle 61 having one or two coarse screw-threads at 61^a, which screw into 10 the central opening of the crown of the burner-ring 51. These means of mounting the vaporizer render it possible to remove the vaporizer for repair, which is an important practical consideration. The auxiliary 15 burner for maintaining the vaporizer at the proper heat consists of a small ring-burner similar to the auxiliary burner disclosed in my above-named patent, of which ring 51 is a part. A cone-shaped wire-gauze 67 is held 20 within the burner-ring 51 by means of the ring 68, having a central opening to allow the proper spread of the flame around the vaporizer. To prevent the products of combustion from the auxiliary burner 67 passing up into 25 the mixing-chamber of the lamp under the action of the current of vapor from nozzle 61, I surround the auxiliary burner with a shield 69, which is supported upon the burner-ring 51 by ring 68. As stated above, my improved 30 needler for keeping clear the orifice of the vapor-nozzle is exteriorly arranged, as distinguished from the common form of needling devices. Formed integral with one of the burner-tubes 26 is a socket 70, within which 35 is adjustably secured a depending guide-tube 71, formed with an angular slot 72 73, extending vertically and horizontally of the guide-tube.
- 70^a is a set-screw for securing the tube 71 40 in the socket 70.
- 75 is the needle-operating rod, formed at its upper end with a curved arm 76, in the outer end of which is a needle-supporting opening 77 and a small set-screw 78, arranged 45 to secure the needle 79 in its opening 77. The upper end of the needle-operating rod 75 is mounted within the tube 71, the arm 76 extending through the slot 72 73, as shown in the drawings.
- 50 74 is a hand-wheel upon the lower end of rod 75, by which the needler is operated. The tube 71 is so adjusted in its sockets 70 that the vertical portion 73 of its slot will be presented toward the vaporizer-nozzle 61, so 55 that when the needle-operating rod 75 is rotated in the tube 71 the arm 76 will travel in the horizontal portion 72 of the angular slot until it reaches the vertical portion 73 of said slot, when the needle 79 will be presented directly above the orifice of the vapor-discharging nozzle 61. The needle-operating rod 75 can then be pulled downwardly, the arm 76 sliding in the vertical portion 73 of the slot and the needle 79 entering the orifice of the 60 nozzle 61 to clear it of any deposits.
- 65 It is essential to the production of a practical needling device that the needle and its

supporting and operating arm be readily detachable from the lamp for adjustment or repair. For this purpose I extend the horizontal portion 72 of slot (in tube 71) into a slight vertical offset 72^a, which leads into a long vertical slot 72^b, extending to the bottom of the supporting-tube 71, as shown in projected view, Fig. 3^a. The shoulder formed 70 by the offset 72^a will normally limit the rotation of rod 75 and arm 76 (when the needle is moved away from the nozzle) by reason of the engagement of arm 76 therewith. When, however, it is desired to remove the needle 80 supporting and operating device, the rod 75 is moved upwardly from the stated inoperative position, causing arm 76 to travel in offset-groove 72^a, and is then rotated slightly to bring arm 76 into the long vertical groove 72^b, 85 when the rod 75 and arm 76 can be pulled downwardly and out of the supporting-tube. The needling device is replaced in its supporting and guiding tube by a reversal of these movements. The importance of this 90 form of needling device is due to the fact that the needle can be normally supported outside of the zone of greatest heat from the vaporizer and can at will be moved into position to clear the orifice of the vaporizer-nozzle. With this form of needling device it is important that an open space be provided 95 between the vaporizer and mixing-chamber for the free movement of the needle into and out of operative position.

100 80 is an ordinary incandescent mantle supported upon a rod 81, which is adjustably mounted in the ring 82, surrounding the burner 27.

83 84 are small gas-pilots mounted upon 105 small branch tubes 85, connected through an offset 86 with the main supporting gas-pipe 1.

90 is a gas Bunsen mounted at the lower end of the branch pipe 91, leading from the lower end of the main supply-pipe 1.

92 is a cock controlling the supply of gas 110 through pipe 91 to the Bunsen burner.

93 is a gas-pilot supplied from the pipe 91 and supported in position to ignite the Bunsen burner 90. It will be observed that the 115 Bunsen burner 90 is arranged to direct its flame against the outer wall of the vaporizer 60.

120 It is my intention to apply my lamps to the ordinary gas-pipes now in use in dwellings and to utilize the ordinary illuminating-gas to maintain the lighting-pilots 83, 84, and 93 and to supply the gas Bunsen 90. The gas Bunsen 90 is lighted to obtain the initial heat of the vaporizer for starting the lamp, and it 125 is my intention to shut off the gas Bunsen immediately after sufficient vapor has been generated to supply the auxiliary burner, which maintains the vaporizer at its proper vaporizing temperature while the lamp is in 130 operation.

135 The main feature of the vaporizer, as above described, consists in forming it of inner and outer tubular sections, which afford a vapo-

rizing-chamber of annular cross-section, the value of which is due to the relatively large area of heating-surface to which the fuel is exposed.

5 A further advantage of my improved vaporizer is due to the cushioning effect of the inner bell-shaped section, which provides a cushion of compressed air to cause a uniform flow of fuel to the vaporizing-chamber, said 10 fuel being supplied in a thin film in the lower end of the vaporizing-chamber, so as to prevent drops of the oil being driven through the nozzle into the mixing-chamber, the objection to which is the production of flare-ups 15 in the flame.

As stated above, my improvements have primarily been designed for a hanging vapor-lamp; but some of the features of the invention are also applicable to other forms of 20 lamps, as I will now explain.

Referring to Fig. 4 of the drawings, it will be observed that I have illustrated my improvements applied to a single-burner bracket-lamp which is adapted to be attached 25 to and supported by the ordinary gas-pipe bracket now commonly used in dwellings.

100 indicates the bracket gas-pipe, having the ordinary cock 101, and 102 is a vertically-extending pipe joined at 103 to the bracket-30 pipe 100 and supporting at its upper curved end my improved single-burner lamp. This single-burner lamp has many features in common with the double-burner lamp which I have hereinbefore described. In this form of 35 a lamp I employ the described vaporizer 60, having fuel-supply pipe 66 and vapor-discharge nozzle 61, the annular vaporizer-heating burner 51, the deflector 69, and the nozzle-needle 79. The globe 11 rests upon a 40 globe-supporting ring 104, sustained by a suitable bracket 105, surrounding and resting upon the ring-burner 51. The main difference between the single-burner lamp and the double-burner lamp is in the construction of 45 the mixing-chamber. This mixing-chamber comprises an inner vertically-adjustable tube 110, threaded into the bottom wall of the central ring or casting 111. The upper end of the inner tube 110 is formed with a series of 50 deep cuts or notches 112, the dividing-walls of which form vertical ribs 113, upon which rests the mixing and deflecting cone 114, the point of which rests centrally within the tube 110. The outer wall 115 of the mixing-chamber 55 is of tubular shape and is supported within the base ring or casting 111 concentrically with the inner tube 110. The tubular outer wall 115 has an inwardly-curved portion 116, from which extends the contracted burner-tube 117, which terminates in the burner proper, 118. A bracket-ring 119 surrounds the burner-tube 117 and supports a mantle-rod 120 in the usual manner. The mixing-chamber is supported above the vaporizer 60 with a free air-supply space between the vapor-nozzle 61 and the inlet of the mixing-

chamber. The mixing-chamber is supported by means of the auxiliary bleeders or vapor-supply tubes 121, which convey a sufficient amount of inflammable gas from the mixing-chamber to the vaporizer-heating burner 51. 70

122 is the gas Bunsen for obtaining the initial heat in the vaporizer. This Bunsen burner 122 is supplied with gas through the cock 123 in the gas-pipe 102. A gas-pilot 124 75 is arranged to ignite the Bunsen 122, pilot 124 receiving gas from a small tube 125, tapped into the gas-pipe 102. The gas-supply tube 125 is also extended vertically and supports a permanent gas-pilot 126, by which 80 the burner 118 is ignited.

The single-burner vapor-lamp which I have just described operates in the main the same as the double-burner lamp. (Illustrated in Figs. 1, 2, and 3.) I have found, however, 85 that the specific construction of the mixing-chamber just described is very important for this single-burner lamp. The arrangement of the inner tube 110, having the cuts or notches 112 and the centrally-supported deflector and mixing-cone 114, co-operates with the inwardly-curved portion 116 of the outer wall of the mixing-chamber to effect a perfect mixture of the air and vapor, so as to produce a satisfactory inflammable lighting- 95 gas.

In Fig. 5 I have shown a further slight modification of my invention to adapt it to a heater. In this application of my invention the vaporizer and mixing-chamber are 100 practically the same as just described in Fig. 4. The upper contracted portion of burner-tube 117 of the mixing-chamber in this form, however, terminates in an enlarged burner-rose 130, having a central cone-deflector 131, 105 projecting downwardly from the center of the burner. I have found this slight modification of my invention to be very effective as a heating-burner. My improvements may also be satisfactorily applied to a portable 110 lamp. I have shown in Fig. 6 the base portion of such a portable lamp in connection with which my improvements may be used. In this figure, 135 represents a globular tank or font having a suitable supporting-base 115 136. In the central opening 137 is fixed a collar 138, into which is threaded a valve-body 139, through which is formed a passage-way 140, controlled by the pin-valve 141, threaded into valve-body 139 and held in 120 place by the cap 142, which is adapted to confine a suitable packing around the valve-stem.

142^a is a ring or washer surrounding the stem of valve 141 and held in its recess 142^b 125 by the packing and cap 142. The ring or washer 142^a confines the movement of the pin-valve and prevents its removal without first removing the cap.

143 is the ordinary alcohol-cup surrounding the lower end of the vaporizer 144, which is threaded upon the valve-body 139. The

vaporizer and mixing-chamber and lighting-burner are of the same construction as illustrated in Fig. 4.

145 is another opening in the lamp-font 135, 5 into which projects the internally-threaded collar 146, formed with an air-port 147, controlled by a hollow pin-valve 148. 149 is an air-pump of ordinary construction arranged to compress air in the tank or font 135.

150 is a tube projecting from the valve-body 139 down into the lamp-font 135 and supporting at its lower end an oil-strainer 151 of ordinary construction, which is supported just clear of the bottom of the font 135.

15 It will be observed that the collar 146 is extended into the font 135. This is for the purpose of preventing the filling of the tank beyond the dotted line x , it being necessary to have an air-space above the oil for the proper 20 operation of the lamp. When it is desired to operate this portable lamp, the lamp-font being filled to the dotted line x , it is only necessary to compress the air above the oil by means of the air-pump 149 and then start the 25 lamp by lighting the alcohol in the cup 143 and later opening the valve 141. The pressure of compressed air above the oil forces the oil in a regular stream up through pipe 150 and valve-body 139 into the vaporizer, 30 where the oil is vaporized and fed into the mixing-chamber, from which the inflammable mixture passes into the burner in the manner well understood. The lamp may be extinguished either by closing the valve 141, 35 and thereby shutting off the supply of fuel, or by opening the valve 148, thereby relieving the lamp-font of its air-pressure.

Having thus described my invention, the following is what I claim as new therein and 40 desire to secure by Letters Patent:

1. In a vapor-burning apparatus, the combination of a mixing-chamber having an inlet for vapor and air, a burner communicating with the mixing-chamber, and a vaporizer 45 having a fuel-supply and a vapor-discharge nozzle arranged adjacent to and separated from the mixing-chamber with a free air-space between the mixing-chamber and vaporizer, with a movably-mounted nozzle-clearing needle device located exteriorly to the vaporizer and mixing-chamber, said nozzle-clearing device carrying a needle which is normally supported away from the vapor-nozzle in the air-space outside the zone of great heat and 50 is adapted to be moved into the free air-space between the mixing-chamber and vaporizer in operative relation to the vapor-nozzle, substantially as set forth.

2. In a vapor-burning apparatus, the combination of the vertically-arranged mixing-chamber and vaporizer having a free space between them, the former having an inlet for air and vapor and the latter a fuel-supply and a vapor-discharge nozzle, and a vapor-burner 55 communicating with the mixing-chamber, with a nozzle-clearing needle operating in the free space between the mixing-chamber and

vaporizer, and a movable support for said needle, mounted upon the exterior of the apparatus, whereby the needle may be moved 70 into and out of operative relation with the nozzle, and be supported normally outside the zone of greatest heat, substantially as set forth.

3. In a vapor-burning apparatus, the combination of a mixing-chamber, a vapor-burner communicating therewith, and a vaporizer having a fuel-supply and a vapor-discharge nozzle, with a nozzle-cleaning needle, and a horizontally-rotatable and vertically-movable 80 support carrying the nozzle-needle, said needle-support being mounted upon the exterior of the apparatus at a point removed from the zone of greatest heat, substantially as set forth. 85

4. In a vapor-burning apparatus, the combination of a mixing-chamber, a vapor-burner communicating therewith, and a vaporizer having a fuel-supply and a vapor-discharge nozzle, with a nozzle-needle, a rod or bar having an arm extending from it in which the needle is mounted, a support for said rod or bar, a horizontally and vertically extending guide groove or slot on one of said parts and a projection on the other engaging said guide 95 groove or slot, whereby the rod or bar may be rotated and moved vertically upon its support, substantially as and for the purpose set forth.

5. In a vapor-burning apparatus, the combination of a mixing-chamber, a vapor-burner communicating therewith, and a vaporizer having a fuel-supply and a vapor-discharge nozzle, with a nozzle-needle, a tubular support having a vertically and horizontally extending guide groove or slot, a rod or bar mounted in said tubular support, and an arm extending from said rod or bar through said guide groove or slot and supporting the needle, substantially as and for the purpose set forth. 100

6. In a vapor-burning apparatus, the combination of a mixing-chamber, a vapor-burner communicating therewith, a vaporizer having a fuel-supply and a vapor-discharge nozzle, parts connecting the mixing-chamber and vaporizer, whereby one is supported by the other with a free space between them, with a nozzle-needle operating in the free space between the mixing-chamber and vaporizer, a 115 vertically-movable rotatable supporting-piece mounted adjacent to one of the parts connecting the mixing-chamber and vaporizer, and a curved arm extending from said supporting-piece and carrying the needle and 120 adapted to project around one of said connecting parts to present the needle in proper relation with the vapor-nozzle, substantially as set forth.

7. In a vapor-burning apparatus, the combination of a mixing-chamber, and a vapor-burner with a vertically-arranged vaporizer, having a fuel-inlet at its lower end, and a vapor-discharge nozzle at its upper end, an 130

- inner bell-shaped section arranged in the vaporizer between the fuel-inlet and vapor-discharge nozzle, to form a cushioning-chamber to equalize the flow of fuel into the vaporizer, substantially as and for the purpose set forth.
8. In a vapor-burning apparatus, the combination of a mixing-chamber, and a vapor-burner, with a vertically-arranged vaporizer comprising an outer tubular section and an inner bell-shaped section which is open at its lower end and closed at its upper end to form an equalizing cushioning-chamber, said inner bell-shaped section communicating adjacent to its open end with the outer tubular section of the vaporizer, a fuel-supply leading to the open end of the inner section, and a vapor-discharge nozzle arranged in the upper end of the outer section, substantially as set forth.
9. In a vapor-burning apparatus, the combination of a mixing-chamber, and a vapor-burner, with a vertically-arranged vaporizer comprising two tubular sections arranged one within the other and communicating at or near their lower ends, said inner section having a fuel-inlet at its lower end to form an air-cushioning chamber, a vapor-discharge nozzle leading from the upper end of the outer section, and means for applying heat to the outer section.
10. In a vapor-burning apparatus, the combination of a mixing-chamber, and a vapor-burner, with a vertical vaporizer comprising an outer tubular section, a vapor-discharge nozzle leading from the upper end of the outer section, an inner tubular section closed at its upper end and arranged concentrically within the outer section and having ports or openings adjacent to its base which communicate with the chamber of said outer section, a fuel-supply communicating with the base of the inner section, and an auxiliary vapor-burner supported adjacent to the vaporizer and having suitable vapor communication with the mixing-chamber, substantially as set forth.
11. In a vapor-burning apparatus, the combination of the vertically-arranged mixing-chamber and vaporizer having a free air-supply space between them, a vapor-burner communicating with the mixing-chamber, a fuel-supply and a vapor-discharge nozzle for the vaporizer, an auxiliary vapor-burner arranged beneath said free air-supply space adjacent to the vaporizer to heat the same, an exteriorly and movably mounted needling device operating in the free space between the mixing-chamber and vaporizer, and a shield surrounding the auxiliary burner to prevent the products of combustion from being drawn into the mixing-chamber by the vapor-current, substantially as set forth.
12. In a vapor-burning apparatus, the combination of the vertically-arranged mixing-chamber and vaporizer having a free air-supply space between them, a vapor-burner communicating with the mixing-chamber, a fuel-supply and a vapor-discharge nozzle for the vaporizer, an auxiliary vapor-burner surrounding the vaporizer beneath the said free air-supply space, tubes communicating between the mixing-chamber and said auxiliary burner, an exteriorly and movably mounted needling device operating in the free space between the mixing-chamber and vaporizer, and a shield surrounding said auxiliary burner to prevent the products of combustion being drawn into the mixing-chamber, substantially as set forth.

ATHOL B. MACKLIN.
